UNITED STATES PATENT OFFICE.

CLINTON DECKER, OF RAINELLE, WEST VIRGINIA.

CABLEWAY.

1,122,080.

Specification of Letters Patent. Patented Dec. 22, 1914.

Application filed September 1, 1914. Serial No. 859,683.

To all whom it may concern:

Be it known that I, CLINTON DECKER, a citizen of the United States, residing at Rainelle, in the county of Greenbrier and State of West Virginia, have invented new and useful Improvements in Cableways, of which the following is a specification.

In systems utilizing suspended cables as means for transferring loads from one point to another, it is frequently necessary to support such cables intermediate of the points between which the load is carried and when the load reaches the intermediate supporting point it is generally necessary to lower 10 the load and again pick up the load in order 15 to pass the intermediate cable support.

The present invention provides novel means for automatically shifting the load from one carriage to the other when the intermediate cable support is reached, thereby 20 overcoming the necessity for lowering the load and again picking up the load which causes loss of time besides entailing a great amount of work.

25 The invention consists of two carriages, one carrier, and a load shifter, the latter being arranged at the intermediate point of support of the cable so as to transfer the load from one carriage to the other without 30 requiring the lowering of the load or the stopping of the same.

35 The invention consists of the novel features, details of construction and combination of parts, which hereinafter will be more particularly set forth, illustrated and claimed.

In the drawings hereto attached:—Fig. 1 is a perspective view of a cableway provided with an intermediate support and load shifting means embodying the invention. Fig. 2 is an enlarged horizontal sectional view through the load shifting means, taken through the lower portion thereof. Fig. 3 is a similar view taken through the 45 upper portion thereof. Fig. 4 is a vertical longitudinal sectional view through the load shifting means showing one of the carriers and carriages approaching the same, and the other carriage located therein. Fig. 5 is a 50 side elevation showing the frame of the load shifting means separated. Fig. 6 is an end elevation of the carriage and carrier. Fig. 7 is a side elevation thereof. Fig. 8 is an enlarged sectional view on the line 8—8 55 of Fig. 4, looking in the direction of the arrow.

Similar reference characters indicate corresponding parts throughout the several views of the drawings.

Referring to the drawings in detail, A 60 designates a suspension cable for supporting the load and constituting the cableway, the same being attached to spars or supports 2, 3 and 4, the spars, supports or the like 65 2 and 3 representing the terminal posts, while 4 represents the intermediate post in event of the cableway being of unusual length.

The load shifter 5 is attached to the intermediate post 4 and serves as a means to automatically transfer the load from one carriage to the other to enable it to pass by the post 4 without interruption in its travel. 70

Similar carriages B are provided to cooperate with the load shifter, such carriages 75 being arranged upon opposite sides of the post 4, the one serving to sustain the load until the intermediate post 4 is reached, when the other carriage receives the load and supports the same during its travel 80 from the intermediate post 4 to the terminal post 3. Each of the carriages B comprises a frame 6 embodying spaced side pieces 7, between which the suspension cable A passes, and the shank of the carrier is received. Small wheels 8 are located near the 85 upper end of the frame to run upon the cable A. Grippers 9 are arranged at opposite sides of the carriage and engage the shank 10 supporting the head 11 of the carrier so as to retain the latter in place during 90 the travel of the carriage. The lower portion of the frame of the carriage is constructed to receive the shank 10 of the head 11 of the carrier 12 so as to support the latter and the load attached thereto. A spring 13 normally exerts a pressure to close the engaging ends of the grippers 9 upon the shank 10 so as to retain the carrier in place upon the carriage. The outer ends of the 100 grippers 9 are curved as indicated at 14 and are adapted to engage trips 15 formed at the ends and on the side of the load shifter whereby the grippers are caused to release the carrier and admit of the same passing 105 from one carriage to the other when the intermediate support or post 4 is reached in either direction of travel of the carrier.

As shown most clearly in Fig. 4 of the drawings, one of the carriages is always in 110 position within the load shifter so as to receive the carrier when the other carriage

enters the load shifter, the transfer of the load being automatic. When the carriage approaching the load shifter enters the latter, the grippers 9 are moved by means of the trips 15 so as to release the carrier, which latter shifts to the carriage, and as the latter moves away from the load shifter the grippers 9 close upon the shank 10, thereby retaining the carrier in place upon the carriage without any possible displacement. The trips 15 are mounted on the curved ends 14 of the load shifter, and are adapted to engage the curved ends 14 of the grippers to move the latter and thereby release the shank 10 so that the carrier may pass from one carriage to the other.

The load shifter comprises a frame embodying spaced side pieces 16, and this frame includes intermediate and outer separable sections which are detachably united through connectors 17, while between the side pieces 16 the carriages and carrier pass. The frame of the load shifter is secured to the spar or post 4 in any substantial way, for example, as shown in Fig. 1. Preferably the said frame has chains 18 connected thereto which are passed about the spar 4 and are fastened together in any suitable manner to secure the load shifter frame thereon. The side pieces 16 at the ends thereof are flared as indicated most clearly in Figs. 3 and 8, and the purpose being to guide the carriages and carrier between the side pieces when the load is passing through the load shifter, or the carriage is returning after delivering a load.

A plurality of vertical rollers 19 are located upon the inner faces of the side pieces 16 to relieve the friction incident to the passage of the carrier between the side pieces of the said load shifter. These rollers 19 also reduce the wear on the operating rope 20, by means of which the carrier 12 is moved outward upon the cable A. The frame of the load shifter may be of any construction, and as shown comprises a middle section 21, and outer sections 22, such sections being suitably secured when placed together, for instance, by the connectors 17.

Wheels 23 are located upon the side pieces 16 in position to engage the head 11 of the carrier, and support the same while passing from one carriage to the other during the transfer of a load, in order to enable the same to pass by the intermediate post 4.

The carrier comprises a frame provided at its upper end with the shank 10 and head 11, such frame being formed with spaced side pieces 24, between which the several operating ropes or cables pass. Vertically arranged grooved pulleys 25 are located between the side pieces 24, and the rope or cable 20 passes between them. The rope or cable 20 is attached to the carrier at one end, as indicated at 26, and passes around the

pulley attached to the support 3, thence passes between the side pieces of the load shifter and the side pieces of the carrier and over a guide pulley attached to the spar or support 2. A pull upon the rope or cable 20 moves the carrier upon the cable A from the support 2 to the support 3. A rope or cable 27 has connection with the carrier 12 and serves as a means for returning the same to the support 2 after the load has been delivered at the support 3. A sheave pulley 28 is attached to the carrier 12 and supports the rope or cable 29 by means of which the load 30 is suspended.

Disposed transversely within the load shifter centrally thereof is a stationary cross bar 31 forming a bearing for oppositely extending coiled compression springs 32 which work against follower plates 33 formed with guide ears 34 movable in guide slots 35 provided in the side pieces 16 of the load shifter, and the purpose of these springs and follower plates is to serve as a buffer for the carriage when passing into the load shifter, so as to absorb shocks and jars incident thereto.

Arranged in a plane below the stretch of the cable A through the load shifter and fixed to the side pieces of the load shifter at the inner faces thereof are tracks 36 having downwardly curved ends 37, and these tracks are engaged by the wheels 38 on the carrier in event of the sagging of the cable A at opposite sides of the load shifter so as to insure a positive entrance of the carrier therein.

In the operation of a cableway for transferring loads from one point to another and should it become necessary to support such cableway at an intermediate point by reason of the unusual length of the cableway, a load shifter 5 is arranged at the intermediate support and two carriages are arranged to operate upon opposite sides of such load shifter, and between it and the terminal supports, such carriages being arranged to act jointly with a carrier whereby the load starting from the point 2 is transferred from the first carriage to the second carriage when the intermediate support 4 is reached, such transfer being automatically effected without requiring the load to be lowered and again picked up. When the first carriage enters the load shifter, the grippers 9 thereof are operated to release the carrier 12, and the latter shifts from the first to the second carriage, and as the latter leaves the load shifter the grippers 9 thereof close about the head 11 and thereby retain the carrier until the load is delivered at the point 3 and the carrier returns to the intermediate support 4, when such carrier automatically shifts the second back to the first carriage and is returned to the point 2 for the next load.

From the foregoing description, taken in connection with the accompanying drawing, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the invention as claimed.

Having thus described the invention, what is claimed as new is:—

1. In a cableway provided with an intermediate and terminal supports, a load shifter located at the intermediate support, a carrier, carriages mounted upon the load supporting cable and arranged upon opposite sides of the intermediate support, and a carrier adapted to receive the load and adapted to be connected with each of the carriages and to be automatically shifted from one to the other in each direction of travel to enable the intermediate support to be passed.

2. In a cableway comprising an intermediate and terminal supports, a load shifter attached to the intermediate support, carriages arranged to travel upon the cableway between the intermediate and terminal supports, a carrier adapted to receive the load and to travel between the terminal supports, and means for automatically transferring the carrier from one carriage to the other when the intermediate support is reached to enable such carrier to pass by the intermediate support in each direction.

3. In a cableway, the combination of a load shifter, two carriages, gripping means mounted upon each of the carriages, a trip for each of the gripping means mounted upon the load shifter, and a carrier adapted to travel through the load shifter and to pass from one carriage to the other in its travel through such load shifter.

4. In a cableway, the combination of a load shifter, two carriages arranged at opposite ends of the load shifter, intermediate supporting means sustained by the load shifter and arranged between the carriages, gripping means for each of such carriages, a trip mounted upon the load shifter for operating each of the gripping means, and a carrier adapted to travel through the load shifter and to be transferred from one carriage to the other and sustained during the travel by the before mentioned intermediate supporting means.

5. In a cableway, the combination of a load shifter embodying a frame comprising spaced side pieces, vertically disposed rollers upon the inner faces of the side pieces, intermediate supporting wheels, trips at the ends of the load shifter, two carriages, gripping means for each of such trips adapted to be operated by the trips, and a carrier for receiving the load and adapted to travel through the load shifter and to be transferred from one carriage to the other and sustained during the transfer by means of the supporting wheels.

In testimony whereof I affix my signature in presence of two witnesses.

CLINTON DECKER.
